UNITED STATES PATENT OFFICE.

JAMES FREEMAN SMITH, OF SMITH CENTER, KANSAS.

END-GATE.

1,252,854.

Specification of Letters Patent.

Patented Jan. 8, 1918.

Application filed November 22, 1916. Serial No. 132,837.

To all whom it may concern:

Be it known that I, JAMES FREEMAN SMITH, a citizen of the United States, residing at Smith Center, in the county of Smith and State of Kansas, have invented certain new and useful Improvements in End-Gates, of which the following is a specification.

This invention relates to end gates for wagons.

One of the main objects of the invention is to provide an end gate which may be permanently secured in the wagon and may be used as a shoveling board or as a dumping gate, optionally. A further object is to provide an end gate in combination with simple and efficient means for securing the same in operative position, this gate being composed essentially of a body portion and a hinged door member secured thereto in combination with means for securing the said members in operative position. A still further object is to provide means for securing the end gate in the wagon body such means being so mounted as to be easily moved into position not to interfere with the movement of the gate into and out of operative position for use as a shoveling board. Further objects will appear from the detailed description.

In the drawings:

Figure 1 is a rear view of the gate as applied to a wagon body;

Fig. 2 is a section on line 2—2 of Fig. 1;

Fig. 3 is a side view of the wagon body with the gate applied partly broken away to show the operation of the gate when used for dumping purposes;

Fig. 4 is a transverse sectional view through the gate and the adjacent portion of a wagon body showing the gate as used for a shoveling board.

The gate has the upper body portion 1 which is provided with a plurality of spaced longitudinally extending reinforcing strips 2 and 3 of sheet metal, or any other suitable material. A rectangular door 4 is mounted in the lower portion of the body 1, and is hingedly secured thereto at its upper edge by means of the hinges 5. This door 4 is provided with a plurality of spaced reinforcing strips 6, 7 and 8 secured thereto, the end portions of which extend beyond the ends of the door 4 so as to normally engage the outer face of the depending lateral arms 9 of the body 1. A sheet metal bar 10 is mounted in rear of the strip 3, in spaced relation thereto. A securing hook 11 is piv-

totally secured between each end of this bar and the reinforcing strip 3, by means of a securing bolt 12 passed through the eye formed at the inner end of the hook and the body of the gate. This hook is adapted to engage into the eye 13 of an eye bolt the threaded shank 14 of which extends through a plate 15 secured to the side 16 of the wagon body. The eye 13 of this bolt, when the bolt is in operative position, fits into the horizontal arm 17 of an L-shaped slot formed in the side 16 of the wagon body. An interiorly threaded sleeve or collar 18 is threaded on to the shank 14 of the eye bolt and is provided with an integral operating crank 19. By rotating the collar 18 by means of the crank 19 the bolt may be moved through the side of the wagon body in either direction. A bar 20 similar to bar 10 is mounted in spaced relation to the strip 7 of door 4, and a bolt 21 similar to bolt 11 is pivotally secured at its inner end between the end of this bar and the strip 7 by means of a bolt 22 passed through the same. The hook 21 is adapted to engage into the eye 23 of an eye bolt similar to that which receives hook 11, and which has a collar 24 threaded on to its shank 25. A securing bolt 26 is slidably mounted between the bar 20 and the strip 7, at the center of the gate. This bolt is secured in position by means of a headed screw 27 which is passed through a longitudinally extending slot 28 formed at the center of bolt 26, near the lower end thereof, and is threaded into the door 4. This permits limited vertical movement of the bolt in either direction. The bolt is adapted to engage into a recess 29 provided in the bottom 30 of the wagon body, when in operative position. In this position the bolt acts to positively prevent outward movement of the gate 4. The bolt is turned outward at right angles, at its upper end, to provide an integral thumb grip 31 which facilitates movement of the bolt into, and out of, operative position.

Normally, the gate will be permanently secured in the end of the wagon body as shown in Fig. 1 of the drawings. In this position hooks 11 and 21 are in engagement with their respective eye bolts, and the eye bolts are drawn tightly outward through the sides of the wagon body. This effectually secures the end gate in the wagon body. In this position the inwardly extending end pieces 32 of the gate engage into the keepers

33 secured to the inner face of each side of the wagon body, these keepers coöperating with the end pieces of the gate to securely brace the gate against lateral movement, and 5 serving to reinforce the structure as a whole.

A transversely extending bar 34 is secured to the inner face of each end piece 32 of the gate. A link 35 is pivotally secured at one 10 end to the inner end of this bar, and is pivotally secured at the other end to one end of a link 36 the other end of which is pivoted to one end of a link 37. The other end of link 37 is pivoted to the lower end of a link 15 38 the upper end of which is pivotally secured to an upright 39 secured to the side 16 of the wagon body, as at 40. These links constitute a flexible connection at each end of the gate which permits limited outward 20 movement of the gate but serves to positively limit this movement so as to secure the gate in position when used as a shoveling board. Normally, the eyes 13 and 23 of the eye bolts which are engaged by the 25 hooks 11 and 21, respectively, are in a horizontal position. When it is desired to use the gate as a shoveling board, the collars 18 and 24 are rotated so as to permit sufficient inward movement of the eye bolts to 30 disengage the hooks from the eyes of the same. When the hooks have been disengaged from the eyes of the eye bolts, these bolts are moved outward, the eyes thereof being turned into vertical position so as to 35 fit into the vertical arms 17^a of the L-shaped slots 17 formed in the side walls 16 of the wagon body. For this purpose the shank of the bolt is mounted loosely through the plate 15, as shown in Fig. 1 of the drawings. 40 When moved into this position the eyes of the bolts do not project beyond the inner faces of the sides of the wagon body. This permits the end gate to be moved outward bodily, this outward movement being limited 45 by the links 35, 36, 37 and 38, as previously described. Before moving the end gate outward, the securing bolt 26 is raised into inoperative position. When the gate has been moved outward, it is placed at an inclination 50 with the lower edge of the gate resting on the upper face of the wagon bed adjacent the end thereof, and the lower end of bolt 26 in engagement with the end of the wagon bed. By this means the gate is secured at a downward and inward inclination 55 so as to provide a shoveling board, as shown in Fig. 4 of the drawings.

When it is desired to use the gate for dumping purposes, the two hooks 21 of the 60 door 4 are released from the eyes 23 of their respective eye bolts, and these bolts are then

moved outward into inoperative position out of the path of movement of the reinforcing strip 7. When the hooks 21 have been released, and the securing bolt 26 is raised into 65 inoperative position, the door 4 is released so as to be free to swing outward about the pivotal axis of the hinges 5. By this means the gate may be quickly and easily adapted for use as a dumping gate. 70

By my invention I produce a gate which is permanently secured in a wagon body and yet may be quickly and easily used either as an end gate proper, a dumping gate, or a shoveling board, all of these adjustments being 75 accomplished quickly and easily, and the gate being at all times firmly secured in operative position.

There may be slight changes made in the construction and arrangement of the different parts of my invention, without departing from the field and scope of the same, and I intend to include all such variations, as fall within the scope of the appended claims, in this application in which a preferred form 85 only of my invention is disclosed.

What I claim is:

The combination of a wagon body, an end gate mounted therein and having limited outward movement relative to the body, said 90 end gate being composed of a body portion and a door hingedly mounted therein for outward movement at its upper edge, the lower edge of the door being flush with the lower edge of the gate body and the door 95 being of less length than the body of the gate and disposed centrally thereof, a plurality of pivotally connected links secured to the wagon body and to the body of the gate adapted to positively limit the outward 100 movement of the gate relative to the body, securing hooks carried by the body of the gate and by the door of the gate, eye bolts mounted for movement through the sides of the wagon body and adapted to be engaged 105 by the said hooks, means for moving the said eye bolts through the sides of the wagon body, and a securing bolt carried by the door and having limited vertical movement, said bolt being adapted to engage the bed of the 110 wagon body so as to prevent outward movement of the door of the gate when in lowered position and, when in raised position, to engage the end of the wagon body so as to 115 secure the gate in position as a shoveling board.

In testimony whereof I affix my signature in presence of two witnesses.

JAMES FREEMAN SMITH.
